Fig. 5

Fig. 2 is a top plan view thereof;

I claim:

The ornamental design for a sand sled, as shown.
